(57) **CLAIM**

The ornamental design for a shower curtain rod, as shown and described.

DESCRIPTION

FIG. 1 is a front, right, top perspective view of a shower curtain rod, showing my new design;

FIG. 2 is a rear, left, bottom perspective view thereof;

FIG. 3 is a front elevational view of the reduced scale thereof;

FIG. 4 is a rear elevational view of the reduced scale thereof;

FIG. 5 is a left side view of the enlarged scale thereof;

FIG. 6 is a right side view of the enlarged scale thereof;

FIG. 7 is a top plan view of the reduced scale thereof;

FIG. 8 is a bottom plan view of the reduced scale thereof;

FIG. 9 is an enlarged view of detail 9 in FIG. 1; and,

FIG. 10 is an enlarged view of detail 10 in FIG. 2.

The dashed broken lines in the figures are for the purposes of illustrating portions of the shower curtain rod and form no part of the claimed design.

The dash-dot-dash broken lines are for notating enlarged views and form no part of the claimed design.

The article is shown with a symbolic break in its length. The appearance of any portion of the article between the break lines forms no part of the claimed design.
